United States Patent Office

Des. 201,514
Patented June 29, 1965

201,514

HOLDER FOR CUPS AND SPOONS OR THE LIKE

Eleanor L. Kutner, 2401 Pennsylvania Ave.,
Philadelphia, Pa.

Filed Feb. 8, 1965, Ser. No. 83,720

Term of patent 14 years

(Cl. D44—29)

FIG. 2.

FIG. 1.

FIG. 3.

FIGURE 1 is a front perspective view of a holder for cups and spoons or the like showing my new design;

I claim:

The ornamental design for a holder for cups and spoons or the like, as shown.
